Primary Examiner — Susan Bennett Hattan*Assistant Examiner* — Omeed Agilee(74) *Attorney, Agent, or Firm* — LeonardMeyer LLP(57) **CLAIM**

The ornamental design for a package for medical device, as shown and described.

DESCRIPTION

FIG. 1 is a top, front and left side perspective view of an ornamental design for a package for medical device;
 FIG. 2 is a top, rear and right side perspective view thereof;
 FIG. 3 is a bottom, rear and right side view thereof;
 FIG. 4 is a bottom, front and left side view thereof;
 FIG. 5 is a front elevational view thereof;
 FIG. 6 is a rear elevational view thereof;
 FIG. 7 is a top plan view thereof;
 FIG. 8 is a bottom plan view thereof;
 FIG. 9 is a left side view thereof; and,
 FIG. 10 is a right side view thereof.

The broken lines shown in the drawings depict portions of the package for medical device that form no part of the claimed design.
